Richard Hoadley

United States Patent Office.

RICHARD HOADLY, OF TOULON, ILLINOIS.

Letters Patent No. 97,919, dated December 14, 1869.

IMPROVEMENT IN FIFTH-WHEELS FOR CARRIAGES.

The Schedule referred to in these Letters Patent and making part of the same

To all whom it may concern:

Be it known that I, RICHARD HOADLY, of Toulon, in the county of Stark, and in the State of Illinois, have invented a new and improved King-Bolt for Carriages and Wagons; and do hereby declare that the following is a full, clear, and exact description thereof, reference being had to the annexed drawings, making a part of this specification, in which like letters of reference refer to like parts, and in which—

Figure 1 represents a perspective view.

Figure 2, a front elevation.

Figure 3, a plan view.

Figure 4 is a perspective view of king-bolt and plate, and bridges and shackles.

Figure 5 is a section of king-bolt.

Like letters in the figures of the drawings, indicate like parts.

This improvement consists in extending the usual "flange" of the king-bolt A, (which forms the centre, on which the axle and fore wheels of a vehicle turn,) so as to make a longer bearing of this part of the bolt on the axle-tree P P.

This extension is in the shape of a plate, B, which terminates at either end in "clips" C C, which embrace the axle-tree P P on either side, and are shackled with the usual irons D below, and secured by nuts on the thread, on the lower extremity of the "clip," or the plate may be also made separate, but with a depression on the surface at either end, to receive the "bight" of the "clip," the latter being fastened beneath the axle-tree in the usual manner.

The shackles D D, or bridges, uniting the lower extremity of each "clip," form a part of, and are connected by a bridge, E, beneath the axle-tree.

This bridge is provided with a jaw, a, on either side, projecting vertically upward, and embracing the lower side of the axle-tree.

Between these jaws projects, downward, a short bolt and thread, b, which enters the eye of the lower stay F, being then secured by nut. This bridge, with its transverse shackles, of course, has a bearing on the under side of the axle-tree, or on the iron plate, or bar uniting the axle-heads.

The usual stay F, immediately beneath, before mentioned as being secured by a nut to a bolt, b, passing through the bridge, I bend upward, with a bifurcation, the end of each fork g g being recurved, to meet two corresponding points, with eyes H H, projecting from the transverse head I I of the carriage-beam, to which they are bolted.

With this improvement, I use the "circle" L', of similar form to that usually employed, and attached to the under surface of the bar M, on which the

body rests, but constructed with an angular projection, i, or device, on its under surface, (near the connecting-bar N of the axle-trees,) which encloses a rubber "buffer" or stop, K, for destroying the jar or jerk incident on striking of the wheel there, on turning the vehicle. No stops or guards, in this instance, are put on the body of the vehicle.

The guards or strikers L, which "fend off" the wheels from the body, by impinging in turning on the said rubbers, are bows or extensions of the iron bearing of the axle-tree, under the "circle," one on either side of the circle, and bent thence round in a curve, and bolted to the outer end of the axle-tree.

The advantages of this improvement are—

First, the king-bolt in this form is stronger, more durable, and can be made by any blacksmith, while the single clip can only be made by a turning-lathe.

Also, the plate can be made separate from the clips, or the clips may be made a part of the plate. The whole device equalizes the pressure and strain on the axle-tree, by dividing the tension or strain.

Also, that the bridge and shackles combine to preserve the integrity of the upper works more effectually than single pairs of separate bridges.

Also, that there is no hole, to weaken the axle-tree, as the king-bolt does not pass through it, and obviates much noise and rattle.

Also, that in the use of rubber buffers or stops, the draught, in turning the vehicle, is lessened, and the usual rub-irons are rendered unnecessary, doing away, consequently, with the jerking—the obvious cause of the displacement and breakage of the carriage or wagon-springs.

The advantage in the use of the doubling or forking of the lower stay is, that the parallelism between the axle and the circle bar is always maintained on uneven ground.

Having thus fully described my invention,

What I claim therein as new, and desire to secure by Letters Patent, is—

1. The forked division G of the forward end of the lower stay F, beneath the axle-tree, in combination with the projections of transverse head I I of carriage-beam, provided with eyes H H by which they are attached, substantially as described.

2. The employment of rubber or spring stops K, so arranged with the fifth-wheel or reach of a vehicle, as to dispense with rub-irons, and thus avoid the jerking motion consequent upon the turning of the vehicle, substantially as set forth.

3. The angular projections or clamps i, having set-screws, for holding the rubber stops K, in combination with the circle or fifth-wheel L', substantially as set forth.

4. The guards L, or extension of the axle-bear-

ings, beneath the circle L', in combination with the rubber stops K, constructed substantially as described.

5. The king-bolt A, with clips C, stay or bridge E with shackles D, forked division G, transverse head I I with eyes H H, rubber buffers K, clamps i, and guards L, or extension of axle-bearings, constructed and arranged substantially as described.

In testimony that I claim the foregoing, I have hereunto set my hand, this 16th day of August, 1869.

RICHARD HOADLY.
